UNITED STATES PATENT OFFICE.

RICHARD B. ROBBINS, OF ADRIAN, MICHIGAN.

IMPROVEMENT IN DRAFT-TUBES FOR SODA-FOUNTAINS.

Specification forming part of Letters Patent No. 135,010, dated January 21, 1873.

To all whom it may concern:

Be it known that I, RICHARD B. ROBBINS, of the city of Adrian, county of Lenawee and State of Michigan, have invented a new and valuable Improvement in Draft-Tubes for Soda-Fountains; and I do hereby declare that the following is a full, clear, and exact description of the construction and operation of the same, reference being had to the annexed drawing making a part of this specification and to the letters and figures of reference marked thereon.

Figure 1 of the drawing represents a perspective view of my invention.

This invention has relation to the manufacture of soda as a beverage; and consists in the novel construction, as hereinafter described, of a metal tube closed at one end and perforated, through which the soda from the fountain to the tumbler passes in jets or spray, thus enabling the soda to unite with the sirup in the tumbler more perfectly than any device now used.

Referring to the accompanying drawing, A represents the draft-tube proper. B designates the end of the tube, which is attached to the fountain; and C, the lower end of the tube, which, when in use, is inserted in the sirup, for the use and purpose hereinbefore mentioned. D designates holes or perforations in the tube, through which the soda is forced. These perforations or apertures may be made of any desirable size, shape, or number.

What I claim as my invention, and desire to secure by Letters Patent, is—

The improved draft-tube as having two or more perforations near one end, and used substantially as and for the purpose set forth.

In testimony that I claim the above I have hereunto subscribed my name in the presence of two witnesses.

RICHARD B. ROBBINS.
